(57) CLAIM

The ornamental design for a combined cosmetic container and spoon as shown and described.

DESCRIPTION

FIG. 1 is a top perspective view of the combined cosmetic container and spoon showing our design;

FIG. 2 is a bottom perspective view thereof;

FIG. 3 is a top plan view thereof;

FIG. 4 is a bottom view thereof;

FIG. 5 is a front elevation view thereof;

FIG. 6 is a rear elevation view thereof, with the left and right side views thereof being the same as the rear elevation view; and,

FIG. 7 is an exploded perspective view thereof with a spoon removed from the cosmetic container.

1 Claim, 4 Drawing Sheets
